UNITED STATES PATENT OFFICE.

CIRO CIABOTTI, OF MILAN, ITALY.

LEAF-TURNING DEVICE.

1,345,316.

Specification of Letters Patent. Patented June 29, 1920.

Application filed June 27, 1919. Serial No. 307,187.

To all whom it may concern:

Be it known that I, CIRO CIABOTTI, a subject of the King of Italy, and residing at 36 Via Vincenzo Monti, Milan, Italy, have invented certain new and useful Improvements in Leaf-Turning Devices, of which the following is a specification.

This invention relates to apparatus for turning the leaves of a book, of a music score and the like and it has for its object to provide a simple and efficient appliance for reading desks, music racks and the like, whereby the leaves may be securely and rapidly turned over, if desired without a manual intervention of the reader or performer.

With this object in view, the invention consists broadly in an appliance wherein a pulley or the like is arranged to be rotated for example by aid of a pedal or of a handle and this pulley is operatively connected with two rotary arms, the first arm being adapted to initiate the turning over of the leaf, while the second arm serves to complete this movement.

The invention will be described with reference to the accompanying drawing which shows, by way of example, one of its constructional forms, it being understood that the details of construction as hereafter described may be modified in many ways without departing from the spirit of the invention.

In the drawings

Figures 1^a and 1^b are a front elevation of the apparatus,

Figs. 2^a and 2^b are a horizontal section just above the double groove pulley,

Figs. 3^a and 3^b are a horizontal section showing one of the arms and the leaf engaging extension thereon.

Figs. 4^a and 4^b are a horizontal section showing the other arm and the pneumatic means thereon for engaging a leaf,

Fig. 5 shows a detail.

Referring to the drawing, the apparatus comprises a box-shaped body portion *a* which is secured to the shelf preferably beneath the board provided to support the book or the like, or this box may be arranged to form itself the book board. Within the box *a* there is provided at or near its center a pin *b* which is rotatably mounted in the upper and lower walls of the box. This pin has secured on it a double groove pulley *c* onto which wind two flexible wires *d*, *d'*. The wire *d'* connects with a wire *e*

arranged to lead to a pedal or handle which is located at any appropriate or desired point to allow the apparatus being readily operated by the reader or performer in the manner hereinafter described. The wire *d* is acted on by a spring *f* which tends to rotate the pulley *c* in the opposite direction to the wire *e*.

The pulley *c* has projecting from its lower face a pin *g* and from its upper face an angularly bent pin *h*, these two pins being arranged in vertical alinement one above the other. A disk *i* is loosely mounted on the pin *b* beneath the pulley *c* and is provided with a small circumferential slot adapted to be engaged by the pin *g*. A second disk *j* is loosely mounted on the pin *b* above the pulley *c* and has a circumferential slot intended to be entered by the upper pin *h*, this slot being much longer than the slot in the disk *i* and extends preferably along half the circumference of the disk *j*. It is thus evident that when the pulley is rotated in the direction of the arrow shown in Fig. 2, a rotary motion will be imparted first of all to the disk *i* through the pin *g* and after an appropriate interval of time to the disk *j* through the intervention of the pin *h* in the manner hereinafter set forth. A coiled spring *i'* serves to return the disk *i* into its normal position after it has been operated.

An arm *k* is formed integrally with the disk *i* and supports on its opposite end an upstanding bar *l* which carries a rubber ball *m* provided with a funnel-shaped opening *m'*. The bar *l* has projecting from it at an intermediate point of its length a pin on which are rotatably mounted two two-armed levers *n*, *n'* arranged after the manner of a pair of pincers. When they are in their inoperative position, the upper arms of these pincers grasp and compress the rubber ball *m*, while their lower arms are correspondingly held apart by a bracket member *o* which projects from the box *a* and is tapered toward its forward end so as to have, for example, a triangular shape in section.

The disk *j* has formed integrally with it an arm *p* which is about half as long as the arm *k*. On the free end of this arm *p* is rotatably mounted a bar *q* adapted to be swung from its vertical position into a horizontal position as indicated by the arrow *q'*, Figs. 1 and 5. A weight *r* is applied to the

lower end of the bar *q* so as to hold it normally in a vertical position. A coiled spring *s* is connected by a wire with the disk *j* which is normally prevented from rotating 5 under the action of this spring by aid of a pawl *t* engaging a tooth formed on the disk *j*.

Both arms *p* and *k* may be made to telescope in order to permit the appliance being 10 used with books of different width.

The apparatus works in the following way.

When the apparatus is at rest, the arm *k* lies adjacent the box *a* and holds the funnel 15 *m'* of the rubber ball *m* against the marginal rim of the right-hand leaf of the book, while the arm *p* is in the position shown in Fig. 3 where it is slightly turned outward from the shelf so that the bar *q* cannot interfere with the reading.

When it is desired to turn a leaf, the reader or performer pulls the wire *e* by aid of the pedal or the handle so that the pulley *c* is caused to rotate and the pin *g* to slide 20 along the coöperating groove in the disk *j* until it imparts a rotary motion to this disk and to the arm *k* which is thereby caused to move away from the shelf. During this rotary motion of the arm *k* the lower arms of 25 the pincers *n*, *n'* slide along the faces of the bracket *o* and approach each other so that the upper arms release their grip on the rubber ball *m*. The rubber ball is thus allowed to expand and this produces a sucking 30 action on the leaf which will thereby be caused to stick to the funnel *m'* and be carried along by the arm *k*. On encountering the bar *q*, the leaf carries this bar into its horizontal position so as to be able to clear 35 it. When the leaf has passed over the bar *q*, the weight *r* returns the latter into its vertical position. In the meantime the pin *h* has traveled along the slot in the disk *j* and will now have reached the pawl *t* which 40 holds the disk in its inoperative position. The pin *h* raises the pawl *t* and the spring *s* now rotates the disk *j* together with the arm *p* so that the bar *q* tears the leaf off from 45 the funnel *m'* and carries it with a jerk to the left-hand side of the book. The wire *e* 50 will now be released and all the parts are returned into their normal position through the action of the respective springs.

What I claim is:

55 1. In an apparatus of the type described, a box, a pulley rotatably mounted within the box, means to rotate the pulley, a first arm, an apertured rubber ball supported from this first arm, means on the lever to 60 grasp and compress the rubber ball, means to release the grip on the rubber ball, a second arm, an upstanding extension on this lever, and means on the pulley to operate first the first named arm and thereafter the 65 second named arm to turn the leaf.

2. In an apparatus of the type described, a box, a pulley rotatably mounted within this box, means to rotate the pulley from the outside, a first arm, an apertured rubber ball supported from this first arm, a pair of pincers adapted to compress the rubber ball or to allow it to expand, a tapered bracket engaged by the pincers so as to cause them to open or close when the arm is rotated, a second lever, an upstanding rotary extension on this arm, means on the pulley to rotate first the one and thereafter the other arm, and means to return the arms into their inoperative position.

3. In an apparatus of the type described, a box, a pulley rotatably mounted within the box; means to rotate the pulley, an arm to initiate the movement of the leaf, an arm to complete the movement of the leaf, means to operate the arms from the pulley, these means comprising a disk above the pulley, a disk below the pulley, these disks being loosely mounted on the pulley shaft and each formed integrally with the respective arm, a pin projecting above and below from the pulley and engaging a circumferential slot within the respective disk, these slots having different lengths so that the disks and the arms will be operated at successive times.

4. In an apparatus of the type described, a box, a pulley rotatably mounted within the box, means to rotate the pulley from the outside, a disk loosely mounted on the pulley shaft above the pulley, a disk loosely mounted on the pulley shaft beneath the pulley, pins on the pulley to engage circumferential slots in the disks so as to operate same, these slots having different lengths, arms formed integrally with the respective disks, an automatically operated suction device on one of the arms to initiate the movement of the leaf, a counterweighted extension on the second arm to complete the movement of the leaf, a latch to hold the hub of this second arm in inoperative position, a coiled spring to rotate the disk and its arm when the disk has been disengaged from the latch by the pin on the pulley, and means to return the parts into their normal position.

5. A leaf turning device comprising a casing, a shaft mounted in the casing, a pulley rotatably mounted thereon, means for rotating the pulley, disks mounted on the shaft adjacent and on either side of the pulley, arms on the disks, suction means on one arm for gripping a leaf, an extension on the other arm for engaging the leaf, and connections between the pulley and the disks to rotate the disks and the arms.

6. A leaf turning device comprising pneumatic means for first gripping a leaf to partially turn same, means for subsequently engaging the partially turned leaf, to complete

the turning of same, and common means for operating the pneumatic means and the subsequent engaging means.

7. A leaf turning device comprising pneumatic means for gripping a leaf consisting of a bulb having an annular extension at one end and a hole communicating with the interior of the bulb, means for compressing the bulb, an arm for subsequently engaging the leaf, and common means for operating the pneumatic means to grip and partially turn the leaf and subsequently operate the arm to cause same to engage the leaf to complete the turning operation.

15 8. A leaf turning device comprising a casting, arms rotatably mounted therein, pneumatic means on one arm for gripping a leaf, adapted to turn the leaf a determined distance, means on the other arm for engaging 20 the leaf, adapted to complete the turning thereof, and means for rotating the arms.

9. A leaf turning device comprising a cas-

ing, arms rotatably mounted therein, means for rotating the arms, pneumatic means on one arm consisting of a bulb having an annular flange at one end thereof and an opening therein, adapted to grip the face of a leaf, means on the arm for compressing the bulb, and an overbalanceed pivoted extension on the other arm, adapted to engage the back of a leaf whereby the pneumatic means is operated to first grip a leaf and rotate it a predetermined distance to pass over the pivoted extension, when said extension will then engage the back of the leaf and be rotated to complete the turning thereof.

In testimony whereof I have signed my name in the presence of two subscribing witnesses at Milan this fifth day of June, 1919. 40
